UNITED STATES PATENT OFFICE

102,930

DESIGN FOR A FOUNTAIN PEN OR SIMILAR ARTICLE

Charles Silverman, Providence, R. I.

Application November 14, 1936, Serial No. 65,909

Term of patent 7 years

To all whom it may concern:

Be it known that I, Charles Silverman, a citizen of the United States, residing at 179 Wheeler Avenue, in the county of Providence and State of Rhode Island, have invented a new, original, and ornamental Design for a Fountain Pen or Similar Article, of which the following is a specification, reference being had to the accompanying drawing, forming part thereof.

In the drawing:

Fig. 1 is a front elevational view of a fountain pen showing my new design, the dominant features of which reside in the clip shown in full lines;

Fig. 2 is a side view thereof, a fragmentary portion only of the barrel being shown for convenience of illustration.

I claim:

The ornamental design for a fountain pen or similar article, substantially as shown and described.

CHARLES SILVERMAN.
